UNITED STATES PATENT OFFICE.

HERBERT R. HEYMSFIELD, OF NEW YORK, N. Y.

OIL BURNER.

Application filed May 17, 1924. Serial No. 713,833.

This invention relates to oil burners of the gravity feed type, and has for its object the production of a burner which is simple and inexpensive of construction, efficient in operation and of universal application to any of the standard and usual types of furnaces.

A further object includes the production of a burner of the type specified which is designed and constructed to be made in sections or parts for ready and easy installation in the usual type of grate furnace.

Another object includes the production of a burner construction which is surface burning and wherein the oil is vaporized by the agency of a vaporizing device which is constructed of a metal of greater conductivity than that from which the body of the burner device is constructed.

Other objects will appear hereinafter, and I attain these results by the construction illustrated in the accompanying drawing in which—

Fig. 1 is a plan view of a furnace supplied with a burner device embodying the principles of my invention.

Fig. 2 is a section taken on the line 2—2 of Fig. 1.

Fig. 3 is a sectional view of the burner taken on the line 3—3 of Fig. 4, and

Fig. 4 is a view taken on the line 4—4 of Fig. 3 looking in the direction of the arrows.

Like numerals refer to similar parts throughout the several views.

It is among the prime objects of my invention to produce a universal burner of such simple and inexpensive construction as to be within reach of the average householder, and which may be readily applied by the average mechanic to the usual heating plant without alterations thereof. To this end I provide a burner base or thimble 10 having a seat or foot end 11 and an oil distributing and burner part or infold 10'. The foot end rests on a suitable base or support 12 which may be a plate or an annular ring made in two sections for convenience in handling and installation. The oil distributing and combustion part 10' is cast or is otherwise formed integral with the thimble 10 and comprises a sloping surface having oil distributing rings or corrugations 13 on the upper side, a pipe retaining rib 14 on the lower side, an oil basin 15 and a central air inlet and hood support 16 on which is seated the hood or deflector 17. Oil feed openings 18 are provided in the sloping surface 10' and through

the retaining rib 14. Into these openings are secured the oil feed pipes 19 and immediately adjacent the corrugations I provide the vaporizing member 20 in the shape of a ring of high conductivity, such as copper or brass for example. This ring may be held seated by lugs 21 in the immediate path of the inflowing air entering through the air inlet ports 22 of the hood support 16 in the deflector 17. Immediately over these ports I provide the deflector canopy 23 which has a central depression 24 and curves outwardly to direct the inflowing draft onto the open flame of incandescent gas to be thence directed outwardly by the flaring skirt 25 of the deflector 17.

If my improved burner is installed in a coal-burning furnace, the two sections of base plates or rings 12 are placed directly on the furnace grate bars 26, and the oil feed pipes 19 may extend between the grate bars to be connected by branches 27 to the usual oil feed valve 28 and pipe connection 29. The oil feed valve is connected to a drip vessel 30 which collects the overflow oil from the burner by means of pan 31 and pipe 32.

Obviously the oil feed valve 28 may be further controlled by a thermostat to thus automatically regulate the oil feed. To increase the draft through the ports 22 for the more effective use of my device, I cover the unoccupied portion of the grate bars with asbestos cement 35 or the like.

From the above disclosure thus far given, the operation of my device will be readily understood. To start the burner, the vaporizing ring is heated. This may be accomplished by permitting a quantity of oil to collect in the well 15 and igniting the same until the vaporizing ring performs its function to vaporize the oil as it creeps or flows over the corrugations. The inrushing draft through the openings 22 will supply the oxygen needed for complete combustion, and the degree of heat is regulated by the rate of oil feed and its combustion.

As a means of safety and to cut off the flow of the oil after the flame has been extinguished, or at other times, I provide a catch-basin or drip-pan 31. This pan collects the oil overflow from well 15, and returns it to the drip vessel 30 the weight of which operates the feed valve 28 in the manner well known to the art.

Having now described my invention, what I claim as new and useful, of my own in-

vention, and desire to secure by Letters Patent is:—

1. In an oil burner, a burner thimble having an infold with a central opening, said infold sloping towards said opening and being provided with a plurality of oil feeds, oil distributing members adjacent said feeds and a vaporizing member adjacent said distributing members, a deflector member seated on said infold, said deflector having openings to direct the air currents on to the vaporizer and over the oil distributors.

2. In an oil burner, a burner thimble having an infold with a central opening, said infold sloping towards said opening and being provided with a plurality of oil feeds, oil distributing members adjacent said feeds and a vaporizing member adjacent said distributing members, a deflector member seated on said infold, said deflector having openings to direct the air currents on to the vaporizer and over the oil distributors, said infold having a pocket to form an oil well for starting the burner.

3. An oil burner comprising a thimble 25 having an infold terminating in an upturned neck, a seating base plate for said thimble, a deflector member seated on said upturned neck, said infold being provided with oil distributing means and oil vaporizing means, said deflector having openings for causing air currents to flow over said infold, and a removable combustion ring on said infold for vaporizing the inflowing oil.

4. In an oil burner, the combination of a 35 furnace and a burner base, including a thimble portion and an infold burner part, said burner part being provided with oil inlets near the outer periphery, a vaporizer near its inner periphery, said vaporizer 40 having a higher temperature conductivity than said burner part, and means for causing air to be fed on to said vaporizer and towards the oil inlets.

In testimony whereof I have hereunto set 45 my hand on this 16th day of May A. D., 1924.

HERBERT R. HEYMSFIELD.
